UNITED STATES PATENT OFFICE.

SAMUEL FURMAN, OF WORCESTER, MASSACHUSETTS, ASSIGNOR TO UNITED STATES ENVELOPE COMPANY, OF SPRINGFIELD, MASSACHUSETTS, A CORPORATION OF MAINE.

MACHINE FOR MAKING WINDOW ENVELOPE BLANKS.

Original application filed August 24, 1918, Serial No. 251,301. Divided and this application filed August 9, 1920. Serial No. 402,408.

To all whom it may concern:

Be it known that I, SAMUEL FURMAN, a citizen of the United States, residing at Worcester, in the county of Worcester and 5 Commonwealth of Massachusetts, have invented a new and useful Improvement in a Machine for Making Window Envelope Blanks, of which the following, together with the accompanying drawings, is a specification.

The present invention relates to improvements in machines for making window envelope blanks, sometimes known as "patching" machines. In such machines the envelope blanks, having previously cut window openings therein are each subjected to a patching operation, which consists in adhesively applying a strip or patch of transparent paper to the inside face of the blank, 10 in order to cover the window opening therein. The apertured blanks thus patched are thereupon discharged from the machine, and are collected or stacked in suitable form for the subsequent operation thereon of folding 15 instrumentalities contained in the same or in another machine, as the case may be.

The present application is a division of my prior copending application serial number 251,301 filed August 24, 1918, which has 20 since matured into Letters Patent No. 1,428,429, dated September 5, 1922; the invention relates to the stack controlling and blank feeding mechanisms that are shown 25 and described, but not claimed in said prior application. The various features of the invention will be made apparent as the description proceeds, reference being had in this connection to the accompanying drawings, in which—

40 Fig. 1 is a front view of a machine constructed in accordance with the invention.

Fig. 2 is a side view of the machine.

Fig. 3 is a central sectional view of the machine.

45 Like reference characters refer to like parts in the different figures.

The mechanism is supported and carried by and between a pair of longitudinal side frames 1, 1, which provide journals for a 50 main driving shaft 2, the latter being actuated by a belt or other driving device,

not shown, from a suitable source of power. The rotation of shaft 2 is communicated by gearing 3 to a shaft 4, which carries a plurality of disks 5 that serve for the conveyance of successive blanks into position for the adhesive application of patches thereto. To this end, the stack of blanks 6 is supported on a suitable adjustable table 7, with the uppermost blank of the stack in position to be operated upon by a device for separating said uppermost blank from the remainder of the stack and presenting it to the disks 5, 5.

Said device, in the present instance, is 65 shown as an oscillating suction pickup 8, which is carried by a rock shaft 9 and has a suitable flexible connection 10 with the usual vacuum producing and controlling devices, not shown, that are common in mechanisms of this class. The rock shaft 9 has secured thereto an upwardly extending arm 11, Fig. 2, which carries on its free end a roll 12 that is adapted to engage a cam 13 on the shaft 4. Another arm 14, extending 70 forwardly from said rock shaft 9, has secured thereto a spring 15, which normally holds the roll 12 against the cam 13. The oscillations of rock shaft 9, under the influence of cam 13, causes the suction pickup 8 to descend into contact with the uppermost blank on table 7, as shown in Fig. 3, and at this time a suction is exerted through the pickup device so as to seize said blank 75 and separate it from the remainder of the stack. Thereafter, the cam 13 causes the pickup to rock upwardly so as to carry the edge of the blank into a position to be seized by a gripping device on one of the disks 5, as hereinafter described.

The arm 14 oscillates between a pair of adjustable stops or set screws 16, 16' carried by a slidable plate 17, which is adapted to have an up and down movement limited by the travel of a slot 18 therein with respect to a fixed screw or pin 19 carried by the framework. The lower end of plate 17 has pivoted thereto at 20 a pawl 21, which is pressed downwardly by a spring 22. The tooth 23 at the free end of said pawl is thus 95 held in engagement with the teeth of a ratchet wheel 24, which is carried by a shaft 100

25 that is journalled between the side frames 1, 1 of the framework and below the table 7. Adjacent the pawl 21 is a second pawl 26, having a fixed pivot 27, and having its 5 tooth 28 also adapted to engage the teeth of ratchet wheel 24. The pawl 26 is normally held in engagement with the ratchet wheel 24 by means of a spring 29, which is secured to an extension 30 of said pawl 10 on the other side of its fixed pivot 27, and the pawl 26 thus normally operates as a holding pawl, adapted to retain the wheel 24 and shaft 25 in the position to which they are moved by the upward movement 15 of pawl 21, during the interval that said pawl is moving downwardly with the plate 17, preparatory its next successive operative stroke.

The shaft 25 carries a pair of spur pinions 31, 31 near the ends thereof, and these pinions are in mesh with racks 32, 32 depending from the table 7, which, as shown in Fig. 1, is adapted to move vertically on suitable guides or rods 33 carried upon the 25 fixed framework. It will thus been seen that the rotation of shaft 4 is transmitted, through the reciprocating plate 17 and pawl and ratchet mechanism above described, to elevate the table 7 by a step by step movement in the normal operation of the machine, and thereby to maintain the stack of blanks on said table always in position to be operated upon by the suction pickup 8, notwithstanding the continuous removal of 35 blanks from the top of said stack. The extension 30 of holding pawl 26 carries a pin 34 which is received within an elongated slot 35 of an upwardly projecting link 36. The link 36 is pivotally secured at its upper end, at 37, to a lever arm 38 which is pivoted at 39 to a stationary cross bar 40 of the fixed framework. The lever arm 38 has a handle 41 at its free end which is employed in rocking it about its pivotal axis 45 39, for imparting movement to the pawl 26 through the link 36. Extending at right angles to the lever arm 38 is a sliding latch rod 42, which has an inclined lower edge 43 cooperating with a shoulder 44 on the upper edge of lever arm 38 and near the free end thereof. The latch rod 42 is supported for sliding movement by means of pins or screws 45 carried by the framework and projecting through elongated slots 46 in 50 said rod 42, the latter being urged outwardly by a tensile spring 47, and being adapted for inward movement against the force of said spring by the exertion of pressure on a knob 48. In the position of the 55 parts shown in Fig. 2, the knob 48 has been pressed inwardly, thereby causing the free end of lever arm 38 to be elevated, under the influence of a spring 49, since the outer end of the inclined edge 43 is, under these 60 conditions, in contact with the shoulder 44.

This position of the parts holds the pawl 26 in operative relation to the ratchet wheel 24, and is thus the operative position for the intermittent elevation of bed or table 7, as above described. 70

When the handle 41 is seized by the operator, and the lever arm 38 swung downwardly, the latch rod 42, under the influence of spring 47, moves outwardly, and owing to the incline of the edge 43, locks the said lever arm 38 in its depressed position. In this depressed position, the pawl 26 is held inoperative with respect to the ratchet wheel 24, so that there is nothing to prevent the reverse rotation of shaft 25 which takes place 80 owing to the gravity descent of bed 7 from the position to which it has been elevated. In this connection it is to be noted that the movement of pawl 26 into its inoperative position automatically prevents further operation of pawl 21, since the latter, disposed directly above the former, is carried out of engagement with the wheel 24 by the contact of the holding pawl against its lower edge. It will thus be seen that the feeding of blanks from the table 7 can be discontinued at will by the operator merely by depressing the handle 41, and furthermore, that after this is done, the machine will not begin to feed blanks again until the knob 48 is pressed inwardly, so as to cause the parts to again resume the positions illustrated in Fig. 2. 85

The extension 50 of the lever arm 38, on the other side of its pivotal axis 39, lies in the vertical path of a member 51, pivotally secured to the bed 7 at 52 and resting, as shown in Fig. 1, against a pin 53 carried by said bed. In the operation of the machine, as the height of the stack of blanks on bed 7 is gradually decreased, said bed is correspondingly elevated, and when there are only a few blanks left on the bed 7, there would be danger in further elevation owing to the approach toward bed 7 of a member 6', which rests by gravity on the stack of blanks and extends into the opening provided by the windows thereof. In other words, this member 6' 105 which is used to maintain the blanks of the stack in true alinement, and also to prevent the separation from the stack of more than one blank at one time, must, for the performance of its functions, be supported solely by the stack and therefore the stack must not be allowed to get so low that the bottom 50' of said member 6' will strike the support or bed 7. To prevent the supply of blanks from running so low as to bring about the above condition, the member 51 is 110 so disposed as to make forcible contact with the extension 50 at a predetermined point in the elevation of the bed when the height of the stack has been decreased to a safe 115 limit, and this forcible contact rocks the 120 member 51 so as to bring the member 51 into 125 contact with the extension 50 at a point in the elevation of the bed when the height of the stack has been decreased to a safe 130 limit, and this forcible contact rocks the 135

lever arm 38 downwardly, and thereby automatically causes the gravity descent of the bed and the discontinuance of the blank feed. The operator is thereby warned to 5 replenish the stack of blanks on the bed 7, and thereafter he can cause a resumption of the blank feed simply by pushing in the knob 48 as above described.

The suction pickup 8 is, as above described, movable in unison with the arm 14 about the same pivotal axis. As a result of this construction all possibility of too great an elevation of the table 7 and stack of blanks is eliminated; that is to say, the 10 rotation of shaft 25 will always be automatically discontinued when the stack is high enough to be reached by the down stroke of the pickup. This is true for the reason that the top of the stack of blanks acts as a limit 15 to the downward movement of suction pickup 8, as effected by the low portion of cam 13. If the top of the stack is so high as to prevent the full downward movement of the pickup, this will also prevent the contact 20 of arm 14 with the lower stop 16', and hence will prevent the operative reciprocation of plate 17 until enough blanks have been picked off to allow the full stroke of the 25 pickup.

Each blank as seized by the suction pickup 8 has its adjacent edge presented to a gripping device, preferably carried by the middle disk 5 on shaft 4. Said disk 5 is preferably recessed on its periphery, as indicated at 54, Fig. 4, and has journalled eccentrically therein a shaft 55 which extends there through and through the other disks 5, 5 toward one side of the machine, and carries on its end an arm 56 having a roller 57 thereon adapted to contact with an interior face cam 58. The shaft 55 is surrounded by a spring 59 which has one end secured thereto, and the other end secured to an arm 60 which rotates in unison with 40 said disk 5 and shaft 4, so that said spring 59 always tends to return the shaft 55 to its normal position after the rocking of said shaft by the contact of roller 57 with cam 58. The cam 58 is so set with respect 45 to the rotation of shaft 4 as to sharply rock said shaft 55 just as a blank is presented by suction pickup 8 to the disk 5, thereby causing the pinching of the edge of said blank 50 by a gripper member 61 carried by shaft 55 and operating in the recess 54. The gripper member 61 and disk 5 thus draw the blank from beneath the pickup 8, whose suction may be automatically discontinued 55 at the proper moment to release the blank, and then resumed for the seizure of the next 60 succeeding blank by mechanism well known in the art, which forms no part of the present invention.

For accomplishing a rapid movement of 65 gripper 61 in seizing and releasing the edge

of the blank, the cam 58 is adapted to be oscillated so as to approach the roller 57 as the latter is swung into contact with said cam, and thereby to accelerate the travel of said roller over said cam. To this end, 70 the cam 58 is journalled loosely on the shaft 4 and has pivotally secured thereto at 58' a rod 59', which is bifurcated at its end to embrace and be guided by shaft 2, said rod carrying a roll 60' which makes contact with a cam 61' on shaft 2. A spring 61'' holds the roll 60' in contact with cam 61', which is so timed as to oscillate the cam 58 at the proper period to accelerate the opening and closing movements of gripper 61. 75

Each blank thus seized by the gripper 61 is carried by the disks 5 into a position above the shaft 4, and at this point the gripper 61 is released by the reverse rotation of shaft 55 under the influence of spring 59 and cam 58, as will be well understood. Conincident with this release of the blank, its edge passes into the bite of disks 62 co-operating with the disks 5 to advance the blank rearwardly of the machine in the plane of its horizontal position. The disks 62 are carried on a shaft 63 which is driven by suitable gearing, not shown, from the shaft 4. From this point rearward in the machine, the travel of each blank is in the plane of its horizontal position, the inner face of the blank being uppermost, so as to permit the application of a band of adhesive around the margin of the window opening in the blank and the subsequent securing of a patch to cover said opening. 90

The mechanism for performing these last named functions is fully described and claimed in my aforesaid copending application, and need not be herein referred to. 105

I claim,

1. In a machine of the class described, a support for a stack of blanks, a swinging member adapted for contact with the top of said stack, to withdraw successive blanks therefrom, and elevating mechanism for said support, operable by the swinging of said member, in combination with means for locking said elevating mechanism in inoperative position to render it non-responsive to the swinging of said member. 110

2. In a machine of the class described, a support for a stack of blanks, a swinging member adapted for contact with the top of said stack, to withdraw successive blanks therefrom, and elevating mechanism for said support, operable by the swinging of said member, in combination with means for locking said elevating mechanism in inoperative position to render it non-responsive to the swinging of said member, and a depressible latch for releasing said locking means. 120

3. In a machine of the class described, a support for a stack of apertured blanks, 125

a member resting by gravity on said stack and disposed in the recess formed by the registering apertures, a swinging member adapted for contact with the top of said stack to withdraw successive blanks therefrom, elevating mechanism for said support, operable by the swinging of said member, and means operable by the descent of said member, through successive blank withdrawals, into proximity to said support, for discontinuing the operation of said elevating mechanism.

10
SAMUEL FURMAN.
